UNITED STATES PATENT OFFICE.

ERNST GEßNER, OF AUE, GERMANY.

MACHINE FOR STEAMING CLOTH.

SPECIFICATION forming part of Letters Patent No. 761,471, dated May 31, 1904.

Application filed May 27, 1901. Serial No. 62,046. (No model.)

To all whom it may concern:

Be it known that I, ERNST GEßNER, a subject of the German Emperor, and a resident of Aue, Saxony, Germany, have invented certain new and useful Improvements in Machines for Steaming Cloth, of which the following is a specification.

My invention relates to that class of cloth-steaming machines in which the cloth is wrapped upon a perforated cylinder, and has for its object to provide means for eliminating water of condensation from the steam which is to enter the cloth.

One feature of my invention consists in providing four fluid-passages, one of which introduces heating-steam into the cylinder, another of which removes from the cylinder the water of condensation from the heating-steam, another of which introduces steaming-steam into the cylinder, and another of which removes from the cylinder water of condensation from the steaming-steam.

Another feature of my invention consists in the combination within the cylinder of a heater and means of drainage, which act in combination upon the water of condensation from the steaming-steam.

Another feature of my invention consists in means whereby the water of condensation from the steaming-steam is collected in or conducted to the passage through which it is drained from the cylinder.

Other features of my invention will be made evident by the following description and set forth in the accompanying claims.

Referring to the accompanying drawings, Figure 1 is an end elevation of my machine with the cylinder in cross-section; and Fig. 2 is a side elevation, the cylinder being longitudinally sectioned.

The machine contains an inner stationary imperforate cylinder or heater A to be heated with steam. It is provided with two hollow journals B and C, resting in a cast-iron frame X, and an external perforated copper cylinder D, having two cast-iron heads E and F, fitted to turn freely around the journals and made steam-tight by stuffing-boxes B' and C'. The

rim a of the head F is toothed and driven by a gearing below it, as hereinafter described. 50

The journal C, Fig. 2, is cast in one piece with the body A of the cylinder and provided with a head G, bolted to it, having a steam-inlet b and having also an outlet c for the waste-water pipe d, leading from the interior 55 of the heater A. The steam entering the chamber A from the pipe b through the annular opening around pipe d presses on top of any water in the bottom of chamber A and forces it out through pipe d and opening c. 60

The journal B is formed with a head e, bolted to the cylinder or heater A, of which head a triangular part h is cut out to give passage to the steaming-steam-inlet pipe f, which is arranged longitudinally within the depression g, by which a trough or gutter is formed in the surface of the heater A. This pipe f is provided with perforations through which the steam enters into the space between the perforated outer cylinder or shell D and the heater A. The gutter g is covered over by a half-round sheet-iron shell, hood, or dasher i, so as to intercept water of condensation in the steaming-steam and throw it back onto the heater A, where it is collected by the trough 70 or gutter g. The hot wall of the heater A, which composes the gutter, partially evaporates this water of condensation, and so much of it as does evaporate flows down the inclined trough or gutter g, through the opening h, into 75 the hollow journal B, whence it is discharged through an outlet k and is conducted to the trap H through a connecting-pipe l. 80

The steaming-steam-supply pipe m is connected with the inlet-pipe f through a T-coupling j. The flange of the coupling j is bolted to the flange of the journal B, while the flange of the steam-inlet pipe f is caught between them and the joint thus rendered steam-tight. Another pipe, n, leads from the coupling j to 90 the trap H.

The inner surface of the perforated cylinder or shell D is provided with three longitudinally-arranged inwardly-projecting double scoops o, o', and o'', so as to catch the condensed water which may accumulate at the 95

bottom of the shell D, elevate it, and discharge it onto the heater in the trough or gutter g. The scoops are so constructed by being in pairs facing in opposite directions as to perform this function whether the cylinder be turning in the right or left hand direction. Now it will be evident that I have provided ample means for carrying or directing water of condensation from the steaming-steam onto the heater and into the gutter g.

For the purpose of winding up and uncoiling the cloth the cylinder D has to rotate either forward or backward and is driven by a reversing-gear. This reversing-gear consists of a lever p, with handle turning around the journal r, and carrying four wheels 1, 2, 3, and 4, wheel 1 being double-gage, and thereby adapted to overlap and engage with both wheels a and 5. This said journal r has its bearing in the frame X, and fixed to it at one end is the small wheel 5 and at the other end the wheel 6, which is in gear with the wheel 7, which is on the main shaft K, carrying the fast and loose pulleys L and M. As the drawings show it, the wheels 1 and 2 of the lever are out of gear with the wheel a. When the handle of the lever p is lowered to its lowest position N, the wheel 1 is brought into gear with the wheel a and imparts to the cylinder D the slow motion necessary for winding up the cloth. By raising the handle of the lever p to its highest position O the wheel 3 is brought to work with the wheel a, imparting to the cylinder D the quicker motion in opposite direction suitable for uncoiling the cloth. R, S, and T are wooden bars for spreading the cloth while being wound on the cylinder.

Although I have shown the journals and heater as stationary instead of rotating with the perforated shell, I do not wish to be understood as limiting this patent to that feature of my invention.

I claim—

1. In a machine for steaming cloth, a perforated cylinder, in combination with a longitudinally-arranged inwardly-projecting scoop on its inner surface.

2. In a machine for steaming cloth, a perforated cylinder, in combination with a longitudinally-arranged inwardly-projecting double scoop, an inner steam-heated cylinder and a reversing-gear to give a forward or backward motion to said perforated cylinder so that any condensed water is carried around by the double scoop either in one or the other direction.

3. In a cloth-steaming machine, in combination, a perforated cylinder, an inner stationary steam-heater, hollow journals for said heater, a steaming-steam-inlet pipe entering through one of said journals and arranged longitudinally within the perforated cylinder, a depression g on the top of the heater, a dasher

covering the same an outlet for water of condensation from said depression g through said journal and an outlet for water of condensation from said heater through the other journal.

4. In a cloth-steaming machine, in combination, a perforated cylinder, an inwardly-projecting scoop, an inner stationary heater, hollow journals, a steaming-steam-inlet pipe entering through one of said journals and arranged longitudinally within a depression on the top of the heater, a hood facing said depression on the opposite side of said pipe, an outlet through one of said journals for water of condensation and an outlet through the other of said journals for the water of condensation from said heater.

5. In a cloth-treating machine, the combination with a non-rotating heating-drum supplied with steam connections and having a drainage-trough extending along its upper surface, a perforated steaming-cylinder adapted to rotate about said heating-drum and a steam-supply pipe lying within said drainage-trough.

6. In a cloth-treating machine, the combination with a non-rotating heating-drum supplied with steam connections and having a drainage-trough extending along its upper surface, a perforated steaming-cylinder adapted to rotate about said drum, a steam-supply pipe lying within said drainage-trough and a dasher covering said steam-supply pipe.

7. In a cloth-treating machine, in combination with a perforated steaming-cylinder, of a trough within said cylinder and a scoop secured to the inner surface of said cylinder and adapted to discharge into said trough.

8. In a cloth-treating machine, the combination with a rotary perforated steaming-cylinder, of a drainage-trough within said cylinder and scoops secured to the inner surface of the cylinder in pairs; the scoops of each pair facing oppositely and all the scoops being adjusted to discharge into the drainage-trough as they reach the upper portion of their course.

9. In a cloth-steaming cylinder, in combination, the perforated shell, a heater, a steaming-steam-supply pipe and means of drainage for the water of condensation from said steaming-steam.

10. In a cloth-steaming cylinder, in combination, the perforated shell, a heater, a steaming-steam-supply pipe, a perforated steaming-steam-distributing pipe and means whereby the water of condensation from the steaming-steam is drained from the cylinder.

11. In a cloth-steaming cylinder, in combination, a perforated shell, a heater, a steaming-steam-supply pipe and a receptacle formed in the surface of the heater for receiving the water of condensation.

12. In a cloth-steaming cylinder, in combination, the perforated shell, a heater, a steam-

ing-steam-supply pipe and an inclined evaporating-receptacle for the evaporation and drainage of water of condensation.

13. In a cloth-steaming cylinder, in combination, a perforated shell, a steaming-steam-supply pipe, and a heater arranged adjacent to the same and provided with a depression wherein to catch the water of condensation from the steaming-steam.

14. In a cloth-steaming cylinder, in combination, the perforated shell, a heater, a steaming-steam-supply pipe and means whereby the water of condensation deposited on the interior of the shell is thrown upon said heater.

15. In a cloth-steaming cylinder, in combination, the perforated shell, the heater, the steaming-steam-supply pipe, means for drainage of water of condensation and means whereby the water of condensation on the interior 20 of said shell is thrown into said means of drainage.

16. In a cloth-steaming cylinder, in combination, the perforated shell, a heater, a steaming-steam-supply pipe, means whereby the 25 water of condensation suspended in the steam escaping from said supply-pipe is thrown upon said heater and means whereby the water of condensation on the interior of said shell is thrown upon said heater.

30. 17. In a cloth-steaming cylinder, in combination, the end bearings, a perforated shell, a heater, inlet and outlet passages through one bearing for the heating-steam and water of condensation therefrom and inlet and outlet 35 passages through the other bearing for the heating-steam and water of condensation therefrom.

18. In a cloth-steaming cylinder, in combination, the end bearings, a perforated shell, a 40 heater, four passages within said bearings, respectively, for the heating-steam, the water of condensation therefrom, the steaming-steam and the water of condensation therefrom.

45. 19. In a cloth-steaming cylinder, in combination, a perforated shell, a heater and four

passages connecting with the interior of said shell, respectively, for the entrance of heating-steam, the exit of water of condensation therefrom, the entrance of steaming-steam and the exit of water of condensation therefrom. 50

20. In a cloth-treating machine, in combination, a perforated shell, a steam-supply connection with the interior thereof, an interior drainage-channel adapted to discharge from the shell by gravity, means whereby water of condensation is collected in said channel and a heater whereby the contents of said shell is heated. 55

21. In a cloth-treating machine, in combination, a perforated shell, a drainage-passage 60 through the bearing thereof and a water-of-condensation receptacle connecting with said drainage-passage and elevated above the same whereby the water may be discharged by gravity. 65

22. In a cloth-treating machine, in combination, a perforated shell, a heater A occupying more than one-half the diameter of said shell and containing a depression g , the steaming-steam-supply pipe f located in said depression and means whereby water of condensation is drained from said depression. 70

23. In a cloth-steaming machine, in combination, a perforated shell, a stationary heater therein, containing a longitudinal depression 75 in its outer surface and a steaming-steam-supply pipe located in said depression.

24. In a cloth-steaming machine, in combination, a perforated shell, a heater therein, two induction steam-passages for the supply 80 of steaming-steam and heating-steam respectively and two eduction water-passages for the escape of water of condensation from said steaming-steam and heating-steam.

Signed at Chemnitz, in the Kingdom of 85
Saxony, this 27th day of April, A. D. 1901.
